TRAVELING BAG HAVING TOP-WALL-SUP-
PORTED COMPARTMENT WHICH REMAINS
HIDDEN WHEN SIDE-WALL CLOSURE IS
OPENED

Abraham Boretz, Bronx, N. Y.

Application January 29, 1948, Serial No. 5,063

2 Claims. (Cl. 190—51)

1

The invention relates to traveling bags or cases. Heretofore the packing of a traveling bag has been subject to the disadvantage that when once packed the contents of the bag, excepting the top layer, are obscured and the items cannot be readily checked to make certain all that are required are in place—unless they are taken out one by one and repositioned. It is often found for example, on arriving at the traveler's destination, that extra socks, shaving soap or the like have been inadvertently left at home. Another inherent disadvantage has been the lack of a protected compartment in the bag wherein to carry bottled or breakable goods, which if fractured, would spill over the contents of the packed bag. The careless handling of porters and baggage handling is generally conducive to such result.

It is the principal object of the invention to provide a bag wherein the traveler may with ease and dispatch, pack the bag and check the contents to ensure that all desired items are positioned within. The invention also embraces the provision of means to permit the utmost accessibility of the bag interior to facilitate packing and unpacking; still another object is a case which can be employed as a convenient storage space for the contents if the traveler does not wish to unpack and place the items, for example, in a bureau drawer.

Additionally, part of the inventive concept is a construction wherein bottled or fragile goods may be packed without fear of breakage; and a repository wherein these items may be concealed from surreptitious or unauthorized view as the bag is being packed and unpacked.

Other objects not specifically enumerated, will be understood from the following description of one embodiment of the invention.

In the drawings:

Fig. 1 is a perspective view of the traveling bag with the side flap in closed position, and the interior bottle compartment in dotted lines.

Fig. 2 shows a perspective view of the bag with the side flap in open position.

Fig. 3 is a perspective view of the bottle compartment.

Fig. 4 is a side elevation of the bottle compartment.

Fig. 5 is a cross-sectional view taken along lines 3—3 of Fig. 3.

In the embodiment illustrating this invention, and with particular reference to Figs. 1 and 2, numeral 5 designates the traveling bag consisting of top 6, depending side walls 7, 8 end walls or

gussets 9, 10 and bottom 11 all of stiffened leather or other suitable material joined together by usual methods known to the industry.

In order to provide opening 12, permitting unobstructed view of the packing of the bag, additionally to facilitate complete access to the interior thereof for expeditious packing, checking and removal of various component parts of the traveler's wardrobe, side wall 7 is cut at 1' from 5 a point 13 spaced from one side and at the bottom of the wall to point 14 spaced from the opposite side and also at the bottom, thereby providing a flap 15 having a hinge-like fold as at 15'. Cut 1', as disclosed in Figs. 1 and 2, is arch-like 10 in outline, with the upper edge of the cut spaced 15 below the top of the side-wall.

The complementary parts of a conventional slide fastener are secured by appropriate means to the meeting edges of the cut 1' with the flap 15 opened 20 and closed by fastener 17. The latter member may be locked, when in closed position, by lock 18 secured to depending leather tab 19.

As best shown in Fig. 2, the flap 15, when in opened position, discloses the contents of the 25 packed bag for ready inspection, and the needed articles may be selected therefrom with the utmost ease and dispatch. And further, the bag may be employed if desired, as a convenient repository for the contents without the usual unpacking.

On the inside of the flap may be provided a 30 compartment 15² for ties or other articles, with shoe compartments 20, 21 and utility compartment 22 at opposite ends of the inside of the bag. The provision of this compartment is, it should be noted, optional.

At the top of the bag and beneath the leather covering 23, are, in juxtaposed relation, as illustrated in Fig. 5, stiffening element 24, a reinforcing bar 25 and band 26, the upper medial portion 40 of flexible band 26 and the bar being secured to the inner side of the top by strip 27, suitably stitched or otherwise fastened thereto. The opposite ends of handle 28 are fastened to posts 29, the inner 45 terminals of which are clinched to the under side of band 26. Band 26 is provided at opposite ends with complementary parts 30, 31 of a fastener and the band, in closed position, forms a cylindrical-like compartment 32 wherein can be nested a 50 bottle of cologne or any other breakable object, as depicted in Figs. 1 and 5.

Bar 25 lends rigidity to the top of the bag in addition to precluding any fracturing of objects placed within compartment 32.

Mounting the cylindrical compartment be-

3

neath the top reinforced with the bar and within the confines of the upper recesses of the bag insures (1) absolute protection of the contents by reason of the bar reinforcement and the relatively stiff depending upper portions of the side walls 7 and 8 and (2) protection of the compartment contents from sight.

The traveling bag is inherently capable of holding more articles than the conventional zipper bag. A pair of shoes or slippers can be packed in compartments 20 and 21, utility compartment 22 being for toilet articles. Ties and handkerchiefs may be placed in compartment 15, and bulk of clothing stacked on the bottom of the bag, so that the stacked items are directly within the view of the packer. Ease of packing and instantaneous check of the contents characterize this type of bag. While the bag is shown with side walls diverging from the top to a wider bottom, which enhances the utility and esthetic appeal of the bag, the invention contemplates the employment of bags with other exterior configurations, as for example, a suit case having parallel side walls. The let-down flap may be employed with this as well as other modified forms of bags.

Minor changes may be effected in other matters of construction within the scope of the appended claims without departing from the principles of the invention.

I claim:

1. In a traveling bag having a top, handle, end walls, a bottom, and a pair of depending side walls providing a continuous space therebetween for

4

the reception and storage of articles; said top having mounted therebeneath a reinforcing bar, a relatively flexible band having opposite free ends with separable closure parts and forming a cylindrically shaped compartment positioned contiguous the top and within the continuous space between the side and end walls; one of the side walls having an access opening provided with a let-down flap, the top of the access opening being spaced beneath the bottom of said compartment whereby said compartment is not visible when the flap is let down, the bottom of said flap having a hingelike fold coextensive with the bottom of the side wall, said flap when let down affording selective access to the interior of the bag or to said compartment.

2. A traveling bag as defined in claim 1, in which the handle of the bag is mounted on posts which connects the reinforcing bar and the compartment forming band to the top.
